UNITED STATES PATENT OFFICE.

JASON H. GREENSTREET, OF INDIANAPOLIS, INDIANA.

BOX-MACHINE.

1,113,329.

Specification of Letters Patent. Patented Oct. 13, 1914.

Application filed December 5, 1911. Serial No. 664,117.

To all whom it may concern:

Be it known that I, JASON H. GREENSTREET, a citizen of the United States, residing at Indianapolis, in the county of Marion and State of Indiana, have invented 5 a new and useful Box-Machine, of which the following is a specification.

The object of my invention is to provide means, in a box-blank making machine, to 10 automatically space the several cleats of each blank and to also automatically space and gage the first cleats of each blank from the last cleats of the finished blank.

The accompanying drawings illustrate my 15 invention.

Figure 1 is a vertical section of a machine, having the general characteristics of the machine shown in my Patent 985,999, dated March 7, 1911, equipped with my present invention; Fig. 2 a fragmentary plan on a larger scale and with the stapling mechanism removed; Fig. 3 a section on line 3—3 of Fig. 2; Fig. 4 a section on line 4—4 of Fig. 2; and Fig. 5 a detail of the lock for the 25 spacing fingers.

In the drawings, 10 indicates a usual anvil above which is arranged suitable stapling mechanism 11, which may be of well known form. Delivering to and extending from, 30 the anvil 10 are cleat guides 12, 12. Traversing the initial end of each cleat guide is a preliminary cleat feeder 13 which is conveniently an endless chain so formed as to be capable of driving the cleats 14 through the 35 guides toward the stapling plane. Feeders 13 are driven from the main drive shaft 15 by a friction train 16 by means of which they may be caused to exert a driving effect upon the cleats at greater speed than the 40 driving effect of the primary feeders 17.

The primary feeders 17 are arranged one adjacent each cleat guide 12 beyond the stapling plane and are driven in such manner as to carry the associated box-blank material away from the stapling mechanism. 45 In the form shown in the present drawings each primary feeder 17 is a spurred endless chain arranged to engage the cleats 14 and these chains are advanced, step-by-step, by 50 a gear train 19 acted on by a pawl-arm 20, pitman 21 and eccentric 21'.

Arranged alongside each cleat guide 12 is a spacer finger 22 similar to the spacing finger shown in Patent 958,996, and capable 55 of lateral projection into and out of the adjacent cleat guide as well as move-

ment lengthwise of the guide. Each finger 22 is pivotally connected to the upper end of an arm 23 carried by a rock-shaft 24 and is also provided with two cam surfaces 25 and 26 adapted, when brought into engagement with pins or rollers 27 and 28, respectively, to shift the spacing-tip 22' of the finger into or out of the cleat guide. In order to prevent the tip of each spacing 60 finger from rubbing against the cleats on its return movement and to hold it in place on its forward movement, I provide a cam track 29 of well known form, in which will travel a pin 31 carried by finger 22.

In order to permit the insertion of the spacing fingers into their cleat guides in front of each oncoming cleat, it is necessary that the oncoming cleat be retarded and for that purpose I arrange, adjacent each cleat guide and in front of the stapling plane, a retarder finger 35 which is adapted to be projected sidewise into the adjacent cleat guide in front of a shoulder 36 (on the forward end of the cleat) as shown in 70 Fig. 2. Each finger 35 is normally urged into the adjacent cleat guide by a spring 37 and is driven out of the cleat guide by an actuator cam 38 on a rock-shaft 39 to which is attached an arm 41. Pivoted to arm 41 is a link 42 to which is connected, by a pin and slot connection 43, a pawl 44 which pivotally depends from one arm of a bell-crank lever 45. Connected to the other arm of lever 45 is a link 46 which is also connected 75 to a lever 47, one arm of which is held against the passing cleats 14 by a spring 48 so as to normally hold pawl 44 out of engagement by a continuously rotating ratchet wheel 49 driven by any suitable driving 80 train, the arrangement being such that, as soon as a cleat passes lever 47, the trailing arm of that lever will drop in behind the cleat and project pawl 44 into the teeth of wheel 49, whereupon said wheel will serve 85 to drive link 42 to the right (Fig. 3) and thus rock shaft 39 so as to cause its cam 38 to withdraw finger 35 from in front of the arrested cleat 18. In the meantime, the spacer finger 22 has been projected in front 90 of the arrested cleat, as shown in Fig. 2.

It is desirable that a finished blank proceed on its way from the machine while the initial blank material is being placed for the initial fastening means and, in order that 110 forward movement of the new material may be controlled automatically, I provide a

horizontally swinging stop arm 51 adapted to have its shoulder 52 thrown into the path of movement of one of the arms 23 by a pin 53 carried by a ratchet wheel 54 and engaging a cam 55 on arm 51. Wheel 54 is advanced one step, for each cleat passing through the adjacent guide, by means of a pawl 56 carried by an arm 57 (dotted lines Figs. 2 and 5) swinging concentric with

10 wheel 54 and connected to the adjacent arm 23. The teeth of wheel 54 are multiples of the number of cleats in any series in the desired blank and there are as many pins 53 as there are groups of teeth.

15 Arm 51 may be withdrawn from arresting position by the following means. Connected to said arm 51 is a link 61 which is also connected to a bell-crank lever 62 to which is connected an actuator bar 63 provided at its free end with a tooth 64 arranged above a continuously rotating ratchet wheel 65. Tooth 64 is normally held out of the path of the teeth of wheel 65 by a light spring 66 but may be readily projected into 20 the teeth of the wheel by means of a finger 67 which is projected downwardly by a spring 68 and normally trails upon the box blank material, as shown in Figs. 1 and 4, the arrangement being such that, when the 25 material has passed from beneath finger 67 it will be forced down upon bar 63 and drive its tooth 64 into contact with the teeth of wheel 65, whereupon bar 63 will be driven forwardly so as to withdraw arm 51 from 30 in front of arm 23 and thus permit the initial material of the new blank to proceed through the machine. If desired, the operator may manually force tooth 64 into the teeth of wheel 65 in order to obtain the 35 40 above described operation at any time.

I claim as my invention:

1. In a box-blank machine, the combination of a material guide, an interrupter projectable into the material guide, an actuator 45 for withdrawing the interrupter from the material guide, a continuously rotating driving member, and means controlled by the passage of material through the material guide for intermittently connecting the actuator with the driving member to withdraw the interrupter from the material guide.

2. In a box-blank machine, the combination of a material guide, an interrupter projectable into the material guide, an actuator 55 for withdrawing the interrupter from the material guide, a continuously rotating driving member, and means for intermittently connecting the actuator with the driving member to withdraw the interrupter 60 from the material guide.

3. In a box-blank machine, the combination of a material guide, an interrupter projectable into the material guide, an actuator 65 for withdrawing the interrupter from the material guide, a driving member, and

means controlled by the passage of material through the material guide for intermittently connecting the actuator with the driving member to withdraw the interrupter from the material guide.

4. In a box-blank machine, the combination of a material guide, an interrupter projectable into the material guide, an actuator for withdrawing the interrupter from the material guide, a driving member, and 70 means for intermittently connecting the actuator with the driving member to withdraw the interrupter from the material guide.

5. In a box blank machine, the combination of a material guide, a spacing finger movable into, along and out of the material guide, a stop for temporarily preventing movement of the spacing finger in one direction along the material guide, means controlled by the passage of material through the guide for intermittently projecting the stop into active position, and means for automatically withdrawing the stop from active position.

6. In a box blank machine, the combination of a material guide, a spacing finger movable into, along and out of the material guide, a stop for temporarily preventing movement of the spacing finger in one direction along the material guide, means for intermittently projecting the stop into active position, and means for automatically withdrawing the stop from active position.

7. In a box blank machine, the combination of a material guide, a spacing finger movable into, along and out of the material guide, a stop for temporarily preventing movement of the spacing finger in one direction along the material guide, means controlled by the passage of material through the guide for intermittently projecting the stop into active position, a continuously rotating driving member, an actuator connected with the stop to withdraw the same from active position and arranged for intermittent connection with the driving member, and means controlled by the passage of material through the guide for intermittently connecting the actuator and driver.

8. In a box blank machine, the combination of a material guide, a spacing finger movable into, along and out of the material guide, a stop for temporarily preventing movement of the spacing finger in one direction along the material guide, means controlled by the passage of material through the guide for intermittently projecting the stop into active position, a continuously rotating driving member, and an actuator connected with the stop to withdraw the same from active position and arranged for intermittent connection with the driving member.

9. In a box blank machine, the combination

tion of a material guide, a spacing finger movable into, along and out of the material guide, a stop for temporarily preventing movement of the spacing finger in one direction along the material guide, means controlled by the passage of material through the guide for intermittently projecting the stop into active position, a driving member, an actuator connected with the stop to withdraw the same from active position and arranged for intermittent connection with the driving member.

10. In a box blank machine, the combination of a material guide, a spacing finger movable into, along and out of the material guide, a stop for temporarily preventing movement of the spacing finger in one direction along the material guide, means controlled by the passage of material through the guide for intermittently projecting the stop into active position, a driving member, and an actuator connected with the stop to withdraw the same from active position and arranged for intermittent connection with the driving member.

11. In a box blank machine, the combination of a material guide, a spacing finger movable into, along and out of the material guide, a stop for temporarily preventing movement of the spacing finger in one direction along the material guide, means for intermittently projecting the stop into active position, a continuously rotating driving member, an actuator connected with the stop to withdraw the same from active position and arranged for intermittent connection with the driving member, and means controlled by the passage of material through the guide for intermittently connecting the actuator and driving member.

12. In a box blank machine, the combination of a material guide, a spacing finger movable into, along and out of the material guide, a stop for temporarily preventing movement of the spacing finger in one direction along the material guide, means for intermittently projecting the stop into active position, a continuously rotating driving member, and an actuator connected with the stop to withdraw the same from active position and arranged for intermittent connection with the driving member.

13. In a box blank machine, the combination of a material guide, a spacing finger movable into, along and out of the material guide, a stop for temporarily preventing movement of the spacing finger in one direction along the material guide, means for intermittently projecting the stop into active position, a driving member, an actuator connected with the stop to withdraw the same from active position and arranged for

intermittent connection with the driving member, and means controlled by the passage of material through the guide for intermittently connecting the actuator and driving member.

14. In a box blank machine, the combination of a material guide, a spacing finger movable into, along and out of the material guide, a stop for temporarily preventing movement of the spacing finger in one direction along the material guide, means for intermittently projecting the stop into active position, a driving member, and an actuator connected with the stop to withdraw the same from active position and arranged for intermittent connection with the driving member.

15. In a box-blank machine, the combination of a material guide, a spacer finger movable into, along and out of said guide, an interrupter projectable into said guide in advance of the spacer finger, means controlled by the passage of material through the guide by which the interrupter may be withdrawn from the guide, a stop for intermittently preventing movement of the spacer finger along the guide, means controlled by the movement of material along the guide for intermittently projecting the stop into active position, means by which the stop may be withdrawn from active position, driving means, and means for intermittently connecting the interrupter-withdrawal and the stop-withdrawal with the driving means.

16. In a box-blank machine, the combination of a material guide, a spacer finger movable into, along and out of said guide, an interrupter projectable into said guide in advance of the spacer finger, means controlled by the passage of material through the guide by which the interrupter may be withdrawn from the guide, a stop for intermittently preventing movement of the spacer finger along the guide, means controlled by the movement of material along the guide for intermittently projecting the stop into active position, and means by which the stop may be withdrawn from active position.

17. In a box-blank machine, the combination of a material guide, a spacer finger movable into, along and out of said guide, an interrupter projectable into said guide in advance of the spacer finger, means by which the interrupter may be withdrawn from the guide, a stop for intermittently preventing movement of the spacer finger along the guide, means for intermittently projecting the stop into active position, means by which the stop may be withdrawn from active position, driving means, and means for intermittently connecting the interrupter-withdrawal and the stop-withdrawal with the driving means.

18. In a box-blank machine, the combination of a material guide, a spacer finger movable into, along and out of said guide, an interrupter projectable into said guide in advance of the spacer finger, means by which the interrupter may be withdrawn from the guide, a stop for intermittently preventing movement of the spacer finger along the guide, means for intermittently projecting the stop into active position, and

means by which the stop may be withdrawn from active position.

In witness whereof, I have hereunto set my hand and seal at Indianapolis, Indiana, this 13th day of November, A. D. one thousand nine hundred and eleven.

JASON H. GREENSTREET. [L. s.]
